UNITED STATES PATENT OFFICE.

WERNER OCHS, OF BRUNSWICK, GERMANY.

TIN-CAN-CLOSING MACHINE.

1,201,861.

Specification of Letters Patent. Patented Oct. 17, 1916.

Application filed July 22, 1914. Serial No. 852,493.

To all whom it may concern:

Be it known that I, WERNER OCHS, a subject of the German Emperor, and resident of Gliesmaroderstrasse 122, Brunswick, Germany, have invented certain new and useful Improvements in Tin-Can-Closing Machines, of which the following is a specification.

The present invention relates to a tin can closing machine on which two tin cans are seamed and closed at one operation.

The essential feature of the present invention consists in the seaming roller carrier being arranged between two holding devices for two separate tin cans disposed in known manner on the front side of the machine, in such a manner, that the two tin cans may be simultaneously seamed by the one roller.

A further feature of the present invention consists in the design of the driving gear for the automatic tin can feeding mechanism, so that the operations of this feeding mechanism are in coöperative relation to those of the seaming and closing appliances.

Another novel feature of the present invention is the arrangement to engage and disengage the driving gear for the seaming and closing mechanisms by means of a foot lever, so that the operator has his hands free for other purposes.

In the accompanying drawing two constructional forms of the present invention are exemplified.

Figure 1 is a front elevation of the machine, on the line I—I in Fig. 2. Fig. 2 is a plan of the machine. Fig. 3 is a vertical section on the line II—II in Fig. 2. Fig. 3^a is a detail view, on an enlarged scale, of the clutch for controlling the driving gear for the seaming and closing mechanisms. Figs. 4—6 are plan diagrams showing the various periods of the operation of the seaming roller carrier. Fig. 7 is a plan of the second constructional form of the seaming roller carrier.

On the front side of the body 1 of the machine is arranged the plunger-like carrier 3 vertically slideable in a guide 2 and carries the two rotatable disks 4 and 5, onto which the tin cans 6 and 7 are placed.

8 and 9 are the clamping disks, the axes 10 and 11 of which are revoluble in the bearings 12 and 13 respectively. The belt pulleys 14 and 15 fitted to the shafts 10 and

11 respectively are coupled by belts 16 with the main driving shaft 17, which is fitted to the shaft 18.

19 is a cam disk, arranged on shaft 20 and driven from shaft 18 by means of the worm wheel 21, the worm 22 and the belt 23.

The seaming roller carrier 24 is slidably fitted in the bearing 25 of the machine body 1. At the rear end of the seaming roller carrier 24 is fitted a roller 26, which bears against the cam disk 19.

26^a is a spring which tends to press the seaming roller carrier continuously against the cam disk. On the seaming roller carrier 24 is fitted the first seaming roller 27 and the flattening roller 28, or, according to the modification shown in Fig. 7, two each such rollers are provided. The seaming rollers are rotatably journaled in the 75 known manner.

29 is a foot lever, which by means of the rod 30 of arm 31 and rod 32 will operate, on the one hand on the plunger-like carrier 3, and on the other hand by means of lever 34 and rod 35 on the clutch 36, for engaging and disengaging the shaft 20. This is accomplished in the following manner:—The worm wheel 21, together with the left-hand member of the clutch 36 (Figs. 2 and 3^a) is loosely mounted on the shaft 20, but it rotates constantly as it is driven by the worm 22 and the belt 23. The shaft 20 rotates with the worm wheel 21 only when the members of the clutch 36 are engaged.

The engaging and disengaging of the clutch 36 takes place by moving to or fro the right-hand member of the clutch on the shaft 20, (see Figs. 2 and 3^a) this member of the clutch rotating with the shaft 20. To accomplish this, the bar 35 is formed at its upper end as a frame 35^a which straddles the shaft 20 and the right-hand member of the clutch, the frame 35^a having on its right-hand side (Fig. 3^a) an inclined surface 35^c 100 adapted to bear against an inclined member 36^d formed on a disk 36^a, the latter being formed in one piece with the right-hand member of the clutch 36. Coöperation of the inclined surfaces 35^c and 36^d causes the 105 disk 36^a and the right-hand member of the clutch 36 to be moved to the right in opposition to the action of the spring 36^b, thereby disengaging the clutch members. By stepping upon the pedal 29, the inclined surfaces above mentioned slide in a direction from one another and the spring 36^b forces

the right-hand member of the clutch 36 toward the left whereby the clutch members are engaged. The disk 36^a has on its periphery a recess 36^c, and the frame 35^a carries a laterally projecting roller 35^b which rests upon the periphery of the disk 36^a. After each revolution of the disk 36^a, the roller 35^b drops into the recess 36^c, causing the inclined surfaces 35^c and 36^d to slide 10 upon one another, thereby disengaging the clutch automatically before completion of the rotation of the disk 36^a, if the pedal 29 is no longer depressed. On the latter is fitted a sprocket 36¹ which by means of the 15 chain 37, the sprocket 38 and the gears 39 drives the transport belt 41, having lugs 40 for advancing the tins 42.

The operation of the machine is as follows: When the operator has placed the tins 20 6 and 7 onto the disks 4 and 5 respectively, he depresses the foot lever 29 which by aid of the members 30, 31, 32 lifts the plunger-like carrier, so that the tins 6 and 7 with their lids 43 lying on them are pressed 25 against the clamping disks 8 and 9 respectively. The tins 6 and 7 will now revolve in the direction of the arrows Figs. 4, 6 and 7. At the same time, the clutch 36 is engaged by the aid of the members 34 and 35, whereby on the one hand the cam disk 19, 30 and on the other hand by the members 20, 36¹, 37, 38 and 39 the transport belt 41 is driven. The cam disk 19 will first advance 35 the seaming roller carrier 24 so far, that the first seaming roller 27 bears against the lid 43. When the disk 19 is turned farther, the flattening roller 28 comes into contact with the lids or the tins 6 and 7 and finally closes the tins. Then the seaming roller

carrier 24 returns under action of its spring 26¹ into its initial position. As the movement of the feeding gear is dependent on the movement of the lever 29, it is obvious, that fresh tins will be only supplied when the others have already been closed. 45

I claim:

1. A seaming machine provided with two seaming stations, each of which comprises a rotary holding chuck and a rotary can body support which reciprocate relatively, 50 in combination with a single slide which reciprocates on a line between the two stations and carries two seaming means, a first seaming means and a finishing means, arranged one behind the other and working one after 55 the other but acting simultaneously on the cans at both seaming stations passing through them.

2. A seaming machine provided with two seaming stations, each of which comprises a rotary holding chuck and a rotary can body support which reciprocate relatively, 60 in combination, with a single slide which reciprocates on a line between the two stations and carries a pair of first seaming rollers, and a pair of finishing rollers arranged one behind the other and working one after 65 the other but acting simultaneously on the cans at both seaming stations passing 70 through them.

In testimony whereof I have hereunto signed my name this 7 day of July 1914, in the presence of two subscribing witnesses.

WERNER OCHS.
